UNITED STATES PATENT OFFICE.

J. L. WIGGIN AND E. FOLSOM, OF SOUTH NEW MARKET, N. H.

IMPROVED LUBRICATING APPARATUS.

Specification forming part of Letters Patent No. **56,306**, dated July 10, 1866.

To all whom it may concern:

Be it known that we, JAMES L. WIGGIN and EBEN FOLSOM, of South New Market, in the county of Rockingham and State of New Hampshire, have invented a new and useful Apparatus for Lubricating the Journal of a Shaft; and we do hereby declare the same to be fully described in the following specification, and represented in the accompanying drawings, of which—

Figure 1 is a vertical section of such apparatus. Fig. 2 represents it as applied to a shaft journal and box.

In such drawings, A denotes an inverted bottle or vessel provided with a cork or stopper, B. A tube, C, closed at its upper end and open at its lower end, goes through the cork and extends a short distance above it. This tube has a foramen or minute hole, a, made in its top. It also has another such hole made in its side, and in that part of the tube which projects into the vessel A.

The tube C, when the apparatus is in use, is to extend into the cap of a journal-box, and so as to reach nearly down to the journal. The passage in the cap for the reception of the

tube should extend quite down to the journal, the same being as represented in Fig. 2, in which D is the journal, c the cap, and E the box.

Preparatory to the apparatus being so applied to the cap the vessel A should be charged with oil, or a lubricating matter, or fluid.

The shaft, while in revolution, will cause air to pass up the tube C, and through the foramen a in its top, whereby a small amount of oil will be caused to pass through the foramen b into the tube, down which it will flow and upon the journal.

On the journal ceasing to revolve there will be no such forcing of air up the tube, and consequently no discharge of oil from the vessel.

We claim—

The shaft-lubricating apparatus, made in manner and for application to a shaft bearing or box, substantially as hereinbefore described.

JAMES L. WIGGIN.
EBEN FOLSOM.
